CLAIM

I claim the ornamental design for a nail polisher for pets set, as shown and described.

DESCRIPTION

FIG. 1 is a first perspective view of a nail polisher for pets showing my new design;

FIG. 2 is a second perspective view of the nail polisher for pets of FIG. 1, viewed from another aspect;

FIG. 3 is a front view of the nail polisher for pets of FIG. 1; FIG. 4 is a rear view of the nail polisher for pets of FIG. 1; FIG. 5 is a left side view of the nail polisher for pets of FIG. 1;

FIG. 6 is a right side view of the nail polisher for pets of FIG. 1;

FIG. 7 is a top view of the nail polisher for pets of FIG. 1; and

FIG. 8 is a bottom view of the nail polisher for pets of FIG. 1; and,

FIG. 9 is an exploded view of the nail polisher for pets of FIG. 1.

The broken lines depict portions of the nail polisher for pets in which the design is embodied that form no part of the claimed design.

1 Claim, 9 Drawing Sheets
